(57) **CLAIM**

The ornamental design for a display device or portion thereof with an animated graphical user interface, as shown and described.

DESCRIPTION

FIG. 1 is a front view of a display device or portion thereof with an animated graphical user interface showing the first image in the sequence of our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof;

FIG. 14 is the fourteenth image thereof;

FIG. 15 is the fifteenth image thereof;

FIG. 16 is the sixteenth image thereof;

FIG. 17 is the seventeenth image thereof;

FIG. 18 is the eighteenth image thereof;

FIG. 19 is the nineteenth image thereof;

FIG. 20 is the twentieth image thereof;

FIG. 21 is the twenty-first image thereof;

FIG. 22 is the twenty-second image thereof;

FIG. 23 is the twenty-third image thereof;

FIG. 24 is the twenty-fourth image thereof;

FIG. 25 is the twenty-fifth image thereof;

FIG. 26 is the twenty-sixth image thereof;

FIG. 27 is the twenty-seventh image thereof; and,

FIG. 28 is the twenty-eighth image thereof.

(Continued)

The appearance of the animated images transitions sequentially between the images shown in FIGS. 1-28. The process or period in which one image transitions to another forms no part of the claimed design.

The broken dot-dashed lines showing the portion of the display device and the dash-dash broken lines showing arrows bars, lines and icons are included for the purpose of showing portions of the article and form no part of the claimed design.
